(57) **CLAIM**

The ornamental design for a floating container for fishing, as shown and described.

DESCRIPTION

FIG. 1 is a perspective view of a floating container for fishing, showing my new design.

FIG. 2 is a front view thereof.

FIG. 3 is a rear view thereof.

FIG. 4 is a left-side view thereof.

FIG. 5 is a right-side view thereof.

FIG. 6 is a bottom view thereof; and,

FIG. 7 is a top view thereof.

The carrying strap illustrated by broken lines shown in FIG. 3 depicts the floating container for fishing in a carrying position of use and forms no part of the claimed design. The D-ring connectors illustrated by broken lines shown in FIGS. 4-5 depict features of the article that form no part of the claimed design. The snap buckles illustrated by broken lines shown in FIG. 2 depict features of the article that form no part of the claimed design. The hook connectors illustrated by broken lines at ends of the carrying strap depict features of the article that form no part of the claimed design. All other broken lines and unshaded areas within them illustrate portions of the article that form no part of the claimed design.

1 Claim, 7 Drawing Sheets
